Assistant Examiner — Clare Ann Gannon

(57) CLAIM

The ornamental design for a barbecue grill cover, as shown and described.

DESCRIPTION

FIG. 1 is a perspective view of a barbecue grill cover showing my new design;

FIG. 2 is a top plan view thereof;

FIG. 3 is a rear elevational view thereof;

FIG. 4 is a bottom plan view thereof;

FIG. 5 is a right side view thereof;

FIG. 6 is a front elevational view thereof; and,

FIG. 7 is a left side view thereof.

The broken line illustrate portions of the barbecue grill cover that form no part of the claimed design.
